UNITED STATES PATENT OFFICE.

PETER L. DONATO, OF NEWARK, NEW JERSEY.

DESIGN FOR A SEWING-MACHINE COVER.

SPECIFICATION forming part of Design No. 14,602, dated February 5, 1884.

Application filed December 5, 1883. Term of patent 7 years.

To all whom it may concern:

Be it known that I, PETER L. DONATO, of Newark, in the county of Essex and State of New Jersey, have invented and produced a new Design for Sewing-Machine Covers, of which the following is a full, clear, and exact description.

Reference is to be had to the accompanying drawings, forming a part of this specification, in which similar letters of reference indicate corresponding parts in both the figures.

Figure 1 is a side elevation, and Fig. 2 is an end elevation, of my newly-designed sewing-machine cover, these two views being deemed necessary to fully illustrate my design.

The leading feature of my design consists in the sides of the cover curved inward from their base to the narrow horizontal top.

A represents the sides of the cover, which are curved inward from the base B to the top C with a gradually-lessening curve. The top C is horizontal and narrow, and its side edges project a little over the upper edges of the sides A, as shown in Fig. 2. Along the sides A, at a little distance from their upper edges, are beads D, giving the said sides the appearance of being paneled. The ends E of the cover are vertical, and the end edges of the top

C and of the upper parts of the sides A project a little beyond the said ends, as shown in Figs. 1 and 2.

The sides and ends of the cover can have ornaments of any desired style formed upon or attached to them.

Having thus described my invention, I claim as new and desire to secure by Letters Patent—

1. The design for a sewing-machine cover herein shown and described, the same consisting of the sides A, curved inward from their base B to the top C.

2. The design for a sewing-machine cover herein shown and described, the same consisting of the sides A, curved inward from their base B, and the narrow horizontal top C, having projecting side and end edges.

3. The design for a sewing-machine cover herein shown and described, the same consisting of the narrow horizontal top C and the sides A, curved inward from their base B, and having longitudinal beads D upon their upper parts.

PETER L. DONATO.
